(57) **CLAIM**

The ornamental design for an x-ray apparatus for body scanning, as shown and described.

DESCRIPTION

An apparatus for x-ray scanning a body, such as that of a human patient.

FIG. 1 is a perspective view of an x-ray apparatus for body scanning, in a position in which the table is raised, showing the present design;

FIG. 2 is a side elevational view thereof;

FIG. 3 is a side elevational view thereof, taken opposite from that of FIG. 2;

FIG. 4 is a front elevational view thereof;

FIG. 5 is a rear elevational view thereof; and,

FIG. 6 is a top plan view thereof.
